INVENTOR

Edward P. Beach,
BY Drake & Co. ATTY'S.

UNITED STATES PATENT OFFICE.

EDWARD P. BEACH, OF NEWARK, NEW JERSEY.

DESIGN FOR A BRACELET.

SPECIFICATION forming part of Design No. 19,378, dated October 29, 1889.

Application filed September 25, 1889. Serial No. 325,080. Term of patent 3½ years.

To all whom it may concern:

Be it known that I, EDWARD P. BEACH, a citizen of the United States, residing at Newark, in the county of Essex and State of New Jersey, have invented and produced a new and original Design for a Bracelet; and I do hereby declare the following to be a full, clear, and exact description of the invention, such as will enable others skilled in the art 5 to which it appertains to make and use the same, reference being had to the accompanying drawings, and to letters of reference marked thereon, which form a part of this specification.

15 In said drawings, Figure 1 is an edge view of a bracelet or necklace embodying my design. Fig. 2 is a face or plan view of a section or portion thereof.

Similar letters of reference indicate like 20 parts wherever they occur.

The two views are deemed sufficient to fully illustrate my design.

The leading features of my design consist 25 in the peculiar configuration presented by the inner and outer surfaces and the edges

of the bracelet. When viewed from the inside or outside, both being the same, the configuration is clearly shown in Fig. 2, the outer sides or edges showing a series of curves A, terminating inwardly in a series of ovals B, 30 which are interlaced at and through the center, with a spiral, showing a series of straight bars C intersecting with the said ovals.

What I claim is—

The design for a bracelet or necklace herein 35 shown and described, comprising an outer and inner surface of the same configuration, having at the edges a series of curves A, terminating inwardly in a series of ovals B, said ovals being interlaced at and through the 40 center, with a spiral, showing a series of straight bars C intersecting with the said ovals, as set forth.

In testimony that I claim the foregoing I have hereunto set my hand this 16th day of 45 September, 1889.

EDWARD P. BEACH.
